US00D957196S

(12) **United States Design Patent** (10) **Patent No.:** **US D957,196 S**
(45) **Date of Patent:** **** Jul. 12, 2022**

(54) **BOTTLE**

(71) Applicant: **YETI Coolers, LLC**, Austin, TX (US)

(72) Inventors: **Dustin Bullock**, Austin, TX (US);
Colin Darling, Austin, TX (US); **Evan Goldberg**, Austin, TX (US)

(73) Assignee: **YETI Coolers, LLC**, Austin, TX (US)

(**) Term: **15 Years**

(21) Appl. No.: **29/756,180**

(22) Filed: **Oct. 27, 2020**

(51) LOC (13) Cl. **07-01**

(52) U.S. Cl.

USPC **D7/511**

(58) **Field of Classification Search**

Assistant Examiner — Darryl J Dardenne

(74) *Attorney, Agent, or Firm* — Banner & Witcoff, Ltd.

(57) **CLAIM**

The ornamental design for a bottle, as shown and described.

DESCRIPTION

FIG. 1 is a front, right, top isometric view of a bottle showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front, right, top isometric view of another embodiment of the bottle showing our new design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a front, right, top isometric view of a bottle showing our new design; and,

FIG. 16 is a rear, right, bottom isometric view thereof. The broken lines depict features that form no part of the claimed design.

1 Claim, 14 Drawing Sheets
